[57] CLAIM

The ornamental design for a faucet lift rod knob, as shown and described.

DESCRIPTION

FIG. 1 is a right side view of a faucet lift rod knob showing our new design, the left side thereof being a mirror image; FIG. 2 is a front view thereof; FIG. 3 is a rear view thereof; FIG. 4 is a top view thereof; and, FIG. 5 is a bottom view thereof.

The broken line showing is for illustrative purposes only and forms no part of the claimed design.
